(57) **CLAIM**

The ornamental design for an exercise resistance band, as shown and described.

DESCRIPTION

FIG. 1 is a top plan view of an exercise resistance band showing my new design.

FIG. 2 is a right side elevational view thereof, the left side elevational view being a mirror image of the right side elevational view and therefore not illustrated.

FIG. 3 is a front elevational view thereof, the rear elevational view being a mirror image of the front elevational view thereof not illustrated.

FIG. 4 is a perspective view thereof, shown in condition of use; and,

FIG. 5 is a perspective view thereof for example purposes only, showing the band being stretched during an exercise. The bottom of the exercise resistance band is flat and unornamented.

The broken lines illustrate environmental structure and form no part of the claimed design.
